UNITED STATES PATENT OFFICE.

ERNEST F. PFLUEGER, OF AKRON, OHIO.

SWEAT-PAD FASTENING.

SPECIFICATION forming part of Letters Patent No. 395,171, dated December 25, 1888.

Application filed October 31, 1888. Serial No. 289,599. (No model.)

To all whom it may concern:

Be it known that I, ERNEST F. PFLUEGER, a citizen of the United States, and a resident of Akron, in the county of Summit and State 5 of Ohio, have invented certain new and useful Improvements in Sweat-Pad Fastenings; and I do declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 Figure 1 of the drawings is a representation of this invention, and is a top view showing a portion of a horse-collar with the pad attached by its fastening. Fig. 2 shows an edge view of the pad and its fastening and a 20 cross-section of the portion of collar. Figs. 3 and 4 are perspective views of the two portions of the fastening. Figs. 5 and 6 are modifications of the two portions of the fastening.

This invention has relation to devices for 25 fastening sweat-pads to the collars of harness; and it consists in the construction and novel combination of devices, as hereinafter set forth, and pointed out in the appended claim.

In the accompanying drawings, the letter 30 A designates a form of pad, and B is the fastener, which is adapted to be adjusted so that it can be readily applied to a collar of any size.

The fastener consists of a C-spring, D, which is designed to clasp the small roll of 35 the collar in attaching the pad in position under the body side. The spring is made in

broad form, so that it will not injure the material of the collar, and is provided with two series of apertures, e e, arranged side by side at its inner end. This C-spring is connected 40 to the pad by the pad catch or fastening F, which consists of an elongated flat body portion, g, having rivet-seats h h at its ends, and between said rivet-seats two catch hooks or prongs, k k, which project from the pad and 45 are designed to engage the apertures e e of the C-spring. These catch hooks or prongs k k terminate in free or headed ends, and are designed to allow the C-spring to be readily removed for readjustment when the collar to 50 which the pad is to be applied requires such action.

I am well aware that it is not new to provide a sweat-pad with a fastening whereby it can be attached to a collar, and therefore I do 55 not claim such device broadly.

What I claim, and desire to secure by Letters Patent, is—

The pad catch or fastening having a body portion, g, provided with rivet-seats, and catch 60 hooks or prongs having free or headed ends, in combination with a removable and adjustable C-spring having a series of apertures adapted to engage said catch hooks or prongs, substantially as specified. 65

In testimony whereof I affix my signature in presence of two witnesses.

ERNEST F. PFLUEGER.
